CLAIM

The ornamental design for the handle, as shown and described.

DESCRIPTION

FIG. 1 is a front perspective view of a handle showing my new design;

FIG. 2 is a front elevational view thereof;

FIG. 3 is a rear elevational view thereof;

FIG. 4 is a top plan view thereof;

FIG. 5 is a bottom view thereof; and,

FIG. 6 is a right side view thereof.

The portions shown in broken lines form no part of the claimed design.
